PROCESS OF MANUFACTURING SOAPS

Walther Schrauth, Berlin-Dahlem, Germany, assignor, by mesne assignments, to "Unichem" Chemikalien Handels, A.-G., Zurich, Switzerland, a corporation of Switzerland

No Drawing. Application April 24, 1931, Serial No. 532,685. In Germany November 19, 1928

5 Claims. (CL. 87—9)

The present invention relates to the manufacture of soap and has for an object to provide an improved process for producing soap from spermaceti or sperm oil.

5 As a matter of laboratory practice it has been known that natural fats and waxes such for example as beeswax can be saponified by melting with caustic alkali and that the alcohol produced by the saponification can be at the same time oxidized and converted into fatty acid alkalies or soaps. The procedure for accomplishing this result has heretofore involved heating the fat or wax with a surplus of lye and continuing the heat until the material became dry, a process 10 which requires a temperature above 300° C. According to the literature on the subject, it is necessary to use a considerable excess of caustic alkali, that is to say a multiple of the amount theoretically required for carrying out the reaction. 15 Heretofore it has not been considered that the product produced as, for example, that produced from beeswax was of any technical use. On the one hand the surplus of alkali remaining after the reaction was completed rendered the 20 product useless and on the other hand the products produced of high molecular weight had not been found useful for washing.

I have now discovered in accordance with the present invention that it is possible to obtain 25 an effective soap from spermaceti or sperm oil by treating the same with the amount of alkali necessary for the saponification of the esters and the oxidation of the alcohols produced by treatment at temperatures between 200 and 280° C. 30 The excess of the alkali over the amount necessary for carrying the reaction to completion should be very small. The alkalies used may be anhydrous or in the form of concentrated lyes.

The sperm oil or the like may be hydrogenated 35 to saturate the unsaturated esters before saponification if desired.

The excess of alkali should be not more than that usually found desirable in the saponification of saponifiable fats. The small amount of free 40 alkali still present in the finished product may be neutralized by the addition of a free fatty acid or abietic acid. The soap produced by this process may be converted into flakes, lumps, chips or powder or a liquid soap may be provided by the 45 addition of water or organic solvents.

Example.—1000 kgs. of sperm oil, either in natural condition or hydrogenated, is heated in a closed autoclave to a temperature of 200° C. The temperature is then increased to 280° C. 50 and at the same time concentrated caustic soda

lye is added in small increments until the normal saponification is completed. The caustic soda lye is added by means of a suitable pump while the pressure is maintained in the autoclave. Care should be exercised that the alkali should not exceed by more than 1 or 2% that necessary for the reaction. The hydrogen set free by the oxidation is removed from the autoclave. The saponification and the conversion of the fatty alcohols into alkali salts of fatty acids is finished when the alkalinity of the whole mass becomes constant. If for example, sperm oil used in this reaction has the saponification number 135, the complete conversion of the same into alkalies of fatty acids according to this process will require 15 220—230 parts solid caustic alkali or about 160 parts caustic soda as such or in the form of caustic lye.

The soap produced may be removed through an outlet and formed into cakes or sprayed 20 through a blastpipe. It is also possible by addition of water or solvents to regulate the fatty acid contents of the soaps in an optional manner. Furthermore, other materials such as soda, Glauber salt, trisodium phosphate, etc., may be 25 added to the soap.

The sperm oil as used in the above example may be replaced by natural spermaceti. If desired the caustic alkali employed in the process may be first added to the spermaceti or the sperm 30 oil and the mixture heated to cause the complete reaction.

I claim:

1. The process of producing soap from sperm oil which comprises saponifying the sperm oil 35 and oxidizing the alcohols formed by treating the material with concentrated alkali at a temperature approximating 200 to 280° C., the quantity of the alkali being approximately 1 to 2% greater than that indicated by stoichiometric calculations for the reaction.

2. The process of producing soap which comprises heating sperm oil in an auto-clave to a temperature between 200° and 280° C. and reacting the sperm oil with caustic alkali to saponify the sperm oil and oxidize the alcohol formed while adding the alkali gradually at such a rate that the excess of alkali will not exceed 2%. 45

3. The process of producing soap which comprises heating sperm oil in an auto-clave to a temperature between 200° and 280° C. and reacting the sperm oil with caustic alkali to saponify the sperm oil and oxidize the alcohol formed, the proportion of alkali being such that at the 50 55

end of the reaction the excess of alkali will not exceed 2%.

4. The process of producing soap which comprises heating sperm oil in an auto-clave to a temperature approximating 200° C. then adding caustic alkali and saponifying the sperm oil and oxidizing the alcohol formed while raising the temperature to approximately 280° C., the amount of alkali added being such that at the end of the reaction the excess of alkali will not exceed 2%.

5. The process of producing soap from sper-

maceti or sperm oil which comprises heating a mixture consisting of sperm oil and concentrated alkali to a temperature approximating 200 to 280° C., reacting the same at that temperature to saponify the sperm oil and oxidize the alcohol formed to convert the same to acids and to neutralize the acids to form soap, the alkali used being not more than approximately 2% more than that necessary for the reaction.

10

WALTHER SCHRAUTH.
